ARC INTERRUPTER

Ralph R. Pittman, Pine Bluff, Ark.

Application June 16, 1932. Serial No. 617,585

4 Claims. (Cl. 175—30)

This invention relates particularly to discharge devices for use in connection with overhead transmission and distribution lines, and has for its primary object the provision of means for positively preventing an excessive superimposed voltage rise on a conductor or connected apparatus such as might be caused by lightning.

Considerable difficulty has heretofore been encountered in devices of this character, as it is necessary that extremely high lightning currents be discharged through these devices, requiring a thermal capacity generally lacking in resistance or porous materials. In addition the device should quickly extinguish any power arc tending to follow the lightning discharge, whether the current flowing in the arc be of very large or very small magnitude. To accomplish this result without the use of moving parts requires a certain amount of resistance in series with the device, and this resistance is objectionable in that it increases the surge voltage applied to the apparatus it is intended to protect by the amount of the impedance drop in the resistance. As lightning currents are now known to be of the order of tens or hundreds of thousands of amperes, it is readily apparent that even a very few ohms of resistance in the discharge path is extremely undesirable.

It is an object of this invention to provide means for interrupting with equal facility large and small current arcs by controlling the area of the arc path in such a manner that this area automatically adjusts itself to the magnitude of the arc current.

A further object of this invention is to provide a simple, inexpensive and effective discharge device for the purpose above described.

With the above and other objects in view which will appear from the description, my invention resides in a novel construction, combination and arrangement of parts substantially as herein-after described and more particularly defined by the appended claims, it being understood that such changes as come within the scope of the claims may be made in the embodiment herein disclosed.

In the drawing, Figure 1 is a side elevational view of the device in the service position.

Figure 2 is a side elevational view of the device, shown in section.

Figure 3 is a front elevational view of the device, also shown in section.

As shown by the drawing, the housing 10 is of some suitable insulating material, as porcelain, and arranged to be supported on a crossarm 24

in any suitable manner, as by the U shaped metal bracket 21, and the bolt 22 extending vertically through the crossarm 24. The U shaped member 21 is rigidly attached to the housing 10 by means of the bolt 13, the latter extending through the midpoint of the disk 14, the wall of the housing 10, and one arm of the U shaped bracket 21. The nut 12 provides means for rigidly clamping this assembly together.

A second disk 15 is supported coaxially with and biased against the disk 14 by the coil spring 16. Circular grooves for seating the spring 16 are provided in the disk 15 and the wall of the housing 10.

A flat metal member 17, having its end portions bent at right angles to the principal axis of the member is rigidly secured to the housing 10 by the bolt 19 extending through both the housing and one of the bent end portions.

The bolt 19 also provides means for attaching a line wire 20 thereto, and in a similar manner the nut 25 on the bolt 13 provides means for attaching a ground wire thereto.

The disks 14 and 15 are preferably made of some insulating material not easily affected by heat or shock, and I have found such a material as horn fiber an inexpensive and effective material.

The bent member 17, having the line wire 20 attached thereto, becomes the line electrode of the device, and similarly, the bolt 13, having the ground wire 11 attached thereto, becomes the ground electrode of the device.

In operation, any voltage appearing on the electrode 17 of a character to break down the spark gap formed by the line electrode 17 and the ground electrode 13 will follow a path between the disks 14 and 15 rather than puncture the solid insulation of the disks. This path is purposely made the weakest electrical path through the device, so that the initial discharge always occurs along a radius between the disks 14 and 15 from the line electrode 17 to the ground electrode 13.

A power arc immediately follows the spark or arc caused by the superimposed voltage, but is immediately extinguished by its confinement between the disks 14 and 15. In the case of small power currents, there is relatively little movement of the movable disk 15. With large currents through the device, there is quite an appreciable movement, but it will be seen that the spring 16 is continually biasing the disk 15 against the disk 14, with the arc therebetween. Since in an alternating current circuit the magnitude of the

current is zero twice each cycle, the movement of the disk 15 into the arc path is relatively unopposed at the instant of zero current. The arc path is thus replaced by the dielectric of the disk 15 at such a period, raising the voltage necessary to maintain the arc above the normal line to ground value, and the arc is in this manner extinguished within the first half-cycle following the initial break down.

10 It will be apparent that sheets of insulating material having shapes other than disks may be used as long as the shortest path between the disks is from an outside edge to a central electrode. It is quite important that a central electrode be used, otherwise an alternate path may be established in air around the preferred gap, resulting in failure to properly operate.

15

I have found that horn fiber disks of such a diameter that the arc path is only $3\frac{1}{2}$ ", with a bias of 12 lbs., will effectively interrupt 8,000 volt arcs to ground. I have also found that a disk 2" in diameter, making an arc path from central electrode to periphery of 1", will effectively interrupt 2300 volt arcs.

25 The device may also be used with disks of other insulating material than fiber. Marble disks require a slightly longer arc path, or about $1\frac{1}{2}$ ", for interrupting a 2300 volt arc.

10 for interrupting a 2500 volt arc.

It will be apparent that the variable area of
30 the arc path, as controlled by the effect of the
arc itself opposing the bias of the spring 16,
makes the device independent of the effective
current value, as with the larger currents the
35 disks separate to relieve the internal pressure,
while at current zero there is present little pres-
sure to oppose the bias of the spring 16.

Since the venting action of the device is entirely controlled by the internal pressure, both the discharge and interrupting capacity are extremely high, and the cost of the device for extremely high currents is relatively low.

45 Other embodiments of the invention herein described will readily appear from this description. One such embodiment might employ a plurality of insulating disks, the central electrode extending therethrough, and the outer electrode extending along the edge of the disks. Such a construction might be desirable for unusually high currents, but I prefer for reasons of economy and 50 simplicity, to use two disks where possible.

From the foregoing description taken in connection with the accompanying drawing, it will be apparent to those skilled in the art that I provide a novel and improved arc interrupter for the purpose described.

What I claim as my invention is:

1. In an arc interrupter adapted to be interposed between a line and ground, a pair of coaxial disks of insulating material, a ground electrode positioned adjacent the center point of one of said disks, a line electrode positioned adjacent the periphery of said disk, said electrodes forming a spark path along a radius of said disks and therebetween, and a spring for biasing one of said disks axially to the other.

2. An arc interrupter comprising a housing of insulating material forming a support for a pair of flat sheets of insulating material, a first electrode extending through adjacent the central point thereof and rigidly supporting one of said sheets within said housing, a second electrode positioned adjacent the periphery of said sheets to form a spark path between said pair of sheets from the first electrode to the second electrode, and a spring supporting and biasing the other of said sheets against the rigidly mounted sheet whereby the action of an arc between said electrodes tending to increase the opening between said sheets is opposed by the deformation of said spring.

3. An arc interrupter comprising in combination, a fixed sheet of insulating material having a first electrode adjacent the mid-point thereof a movable sheet of insulating material of substantially the same dimensions as said fixed sheet resiliently biased toward said fixed sheet, and a second electrode positioned at a point adjacent the outer edge of said sheets.

4. An arc interrupter comprising, in combination, a stack of flat sheets of insulating material, a first electrode extending into stack normal to the plane of said sheets adjacent the mid point thereof, a second electrode parallel to said first electrode adjacent the outer edge of said stack, said electrodes forming a spark path between said sheets, and means including a spring for resiliently biasing said sheets together.
